UNITED STATES PATENT OFFICE.

JOSEPH WOLNY, OF CARNEYVILLE, WYOMING.

COMBINED SLIDING AND SWINGING CAR-DOOR.

1,178,613.

Specification of Letters Patent. Patented Apr. 11, 1916.

Application filed August 24, 1915. Serial No. 47,107.

To all whom it may concern:

Be it known that I, JOSEPH WOLNY, a subject of the Emperor of Austria-Hungary, residing at Carneyville, in the county of 5 Sheridan and State of Wyoming, have invented certain new and useful Improvements in Combined Sliding and Swinging Car-Doors, of which the following is a specification.

10 This invention relates to certain new and useful improvements in combined sliding and swinging car doors.

An object of the invention is to provide 15 a door for railway cars including two sections that may be moved into adjacent position whereby a closure for one-half of the door-way is provided and in which the door sections when so positioned may be moved to either the upper end or the lower end of 20 the door opening.

A further object of the invention is to provide a door for railway cars comprising 25 slidably associated door sections that may be slid in a vertical direction to provide a complete or partial closure for the door-way, and that is capable of swinging movement to lie adjacent the roof of the car so that the door-way of the car is wholly unobstructed.

30 With these general objects in view and others that will appear as the nature of the invention is better understood, the same consists in the novel construction, combination and arrangement of parts hereinafter 35 more fully described, illustrated in the accompanying drawings, and pointed out in the appended claim.

In the drawings forming a part of this 40 application and in which like designating characters refer to corresponding parts throughout the several views:—Figure 1 is a longitudinal sectional view of a portion of a railway car provided with the present improved construction of door, with both sections of the door at the lower end of the door-way. Fig. 2 is a longitudinal sectional view of a portion of a railway car with the door sections positioned at the upper end of the door-way. Fig. 3 is a transverse sectional view of a portion of a railway car with both sections of the door at the lower

end of the door-way. Fig. 4 is a similar view of the door sections slid upwardly and swung out of the door-way into position adjacent the car roof. Fig. 5 is a 55 horizontal sectional view of a portion of the railway car, more clearly illustrating the mechanism for supporting the door when swung outwardly from the door opening. Fig. 6 is a detached detail perspective view 60 of one of the door guides, and, Figs. 7 and 8 are detail perspective views, partially broken away, of portions of the upper and lower door sections respectively.

Briefly described, the present invention 65 aims to provide a door for railway cars which includes two door sections that may be operated to completely or partially close the door-way in the car by a sliding movement afforded by guides at the sides of the 70 door-way. The guides for the sliding door sections positioned on the interior of the car may be moved on pivotal connections to permit the door sections to swing on a pivotal connection with the guides and be moved 75 to a position adjacent the car roof so as to be completely removed from the door-way.

Referring more in detail to the accompanying drawings, the reference numeral 10 designates a railway car of usual construction including the floor 11, a roof 12, and roof supporting beams 13 while door openings 14 are provided in the sides of the car. The sides of the door openings 14 are provided with channel guides including vertical stiles 15 having vertical grooves 16 provided by inwardly-extending flanges 17 and 18, the flange 17 being positioned at the outer side and being of greater depth than the inwardly-positioned flange 18 for purposes to 85 be later described.

A portion of each of the door sections is shown in Figs. 7 and 8, the upper door section being designated 19 and the lower door section 20, each of the door sections being 95 preferably constructed of sheet metal. The lower door section 20 is provided with a rolled lower end 21 while the side edges are turned inwardly as at 22 providing a pin extension 23 at the lower end. As shown in 100 Fig. 5, the upper door section 19 is slidably associated with the lower door section 20

and is guided in its movements by the in-turned side edges 22 to prevent the disassembling of the sections. In assembled position, the pin extensions 23 are slidably received within the grooves 16 in the door stiles 15 which prevents the lower end of the door from swinging. A movable guide is associated with the stile 15 and is positioned adjacent the upper end thereof and is caused to engage the door sections 19 and 20 during their entire sliding movements so that the upper end of the door may be prevented from swinging inwardly. This guide is shown in detail in Fig. 6 and includes an angle-iron 24, the upper and lower ends of which carry pivotal pins 25 adapted to be received in eye bolts 26 carried by the inner face of the stile 15. A latch 27 is provided to hold the guides 24 in operative position and is more clearly shown in Figs. 1 and 2, the latch 27 being hinged to the inner face of the stile 15 and supported in its operative position by a keeper 28 carried by the said stile, it being noted that the projecting end of the latch 27 extends beyond the keeper to engage the outer leg of the angle-iron guide to prevent the same from swinging on its pivotal pins 25.

The mechanism for raising and lowering the door sections 19 and 20 includes spaced depending brackets 29 carried by the car floor 11 and having journaled in the lower end thereof a rod 30 provided on one end thereof with an operating crank handle 31. Eye-bolts 32 and 33 are carried respectively, by the upper and lower door sections 19 and 20 and are adapted to be selectively engaged by one end of the operating chain 34, the said chain passing over guide rollers 35 positioned adjacent the upper end of the car 10 and continuing downwardly as at 36 from the guide rollers to be connected to and wound upon the rod 30. Pawl and ratchet mechanism 37 is provided on the rod 30 to prevent retrograde movement when the chain is being wound in one direction. As shown in Fig. 1, the chain 34 is connected to the eye-bolt 33 carried by the lower door section 20 and by operating the rod 30, both door sections 19 and 20 will be elevated to the desired height by reason of the upper door section engaging the lower rolled end 21 of the lower door section. If it be desired to provide a complete closure for the door-way 14, the chain 34 is disconnected from the eye-bolt 33 and connected to the eye-bolt 32 of the upper door section and the rod 30 may then be operated to cause the upper door section alone to be elevated. It will be noted that lifting chains for the doors are provided at each side thereof and connect with the common operating rod 30.

The door and guides therefor are so constructed to permit the same to be swung completely from the door-way, it being noted that a release of the latches 27 will permit the angle-iron guides 24 to be moved on their pivotal pin connections 25 whereby the upper end of the door sections 19 and 20 will be permitted to swing inwardly beyond the relatively short flange 18. A support is provided for the door when the same is adapted to be swung from the door opening 14 and includes, as more clearly shown in Figs. 3, 4, and 5, a U-shaped hanger 38 supported by the roof beams 31 and hingedly connected thereto at its ends as indicated in Figs. 3 and 4. A pair of guide rods 39 is connected adjacent their rear ends to the hanger 38 while the forward ends thereof are connected by a cross-bar 40 projecting laterally of the guide rods 39 and provided with upturned ends 41. When the supporting rack is in inoperative position as shown in Fig. 3, the same is held in horizontal position adjacent the car roof by a latch member 42 hinged to the upper frame of the door-way and adapted to be swung to lie beneath and support the transverse bar 40.

When it is desired to swing the door from the door-way 14, the lifting chains 34 are disconnected from the eye-bolts 32 and 33 and caused to engage the eye-bolts 43 carried by the lower door section 20 as indicated in Fig. 4. It being understood that the angle guides 26 were moved to the position as shown in Fig. 4, the shaft 30 is operated to cause the chain 34 to be wound thereon and the door will be elevated and swung inwardly at its upper end to be slidably received on and supported by the hanger and rack 38 and 39. The pawl and ratchet mechanism 37 will hold the door in any of its adjusted positions. In order to assist the pawl and ratchet in holding the door sections elevated, as shown in Fig. 3, I have provided a pin 44 that may be inserted within the opening 45 in one of the side stiles 15 to support the lower end of the car doors.

From the above detailed description of the invention, it is believed that the operation thereof will be readily apparent and while the forms of the invention herein shown and described are what are believed to be preferable embodiments thereof, it is nevertheless to be understood that various forms, modifications and arrangements of the parts may be made without departing from the spirit and scope of the invention as set forth in the appended claim.

What I claim as new is:—

A device of the class described, comprising a car having a side door opening, chan-

nel guides positioned at the sides of the door opening, a two-part door slidably and swingingly mounted in said guides, the lower section of said door having a rolled 5 lower end, inturned side edges carried by the lower door section providing guides for the upper door section, laterally extending

pins carried by the lower rolled end of the lower door adapted for sliding engagement in said channel stiles, and means for 10 raising and lowering said door sections.

In testimony whereof I affix my signature.

JOSEPH WOLNY.
